SIGNAL FOR STORE CLERKS

**Robert M. Akers, 1301 E. Reno,
Oklahoma City, Okla. 73101**

Filed Apr. 29, 1970, Ser. No. 22,704

Term of patent 14 years

Int. Cl. D31

U.S. Cl. D72—1

FIG. 1 is a front elevational view of a signal for store clerks showing my new design;

FIG. 2 is a top plan view thereof;

FIG. 2 is a top, plan view thereof;
FIG. 3 is a fragmentary side elevational view thereof:

FIG. 3 is a fragmentary side elevational view thereof, FIG. 4 is a fragmentary rear elevational view thereof:

FIG. 4 is a fragmentary rear elevational view thereof, FIG. 5 is a fragmentary elevational view of the side opposite that shown in FIG. 3:

FIG. 6 is a sectional view taken on line 6—6 of FIG. 1.

FIG. 6 is a sectional view taken on line 6-6 of FIG. 1. The indicia is shown in broken lines in FIG. 1 for illustrative purposes only. The signal is fragmentarily shown in FIGS. 3, 4 and 5 for convenience of illustration.

I claim:

The ornamental design for a signal for store clerks, as shown and described.
